(57) **CLAIM**

The ornamental design for a seat, as shown and described.

DESCRIPTION

In a preferred embodiment, the nature of this product is as a removable seat for a plumbing enclosure which is primarily useful for providing a support for various parts of the human body.

FIG. 1 is a right, top, front perspective view of a seat embodying my new design;

FIG. 2 is a top plan view thereof;

FIG. 3 is a front elevational view thereof;

FIG. 4 is a right side elevational view thereof, the left side elevational view being a mirror image of the right side shown;

FIG. 5 is a rear elevational view thereof; and,

FIG. 6 is a bottom plan view thereof.

The broken line representation of a mounting environment in FIG. 1 is for the purpose of illustration only, and forms no part of the claimed design.
